UNITED STATES PATENT OFFICE.

FRED C. LOUNSBURY, OF PLAINFIELD, NEW JERSEY.

DOOR-FASTENER.

SPECIFICATION forming part of Letters Patent No. 596,118, dated December 28, 1897.

Application filed February 3, 1897. Serial No. 621,779. (No model.)

To all whom it may concern:

Be it known that I, FRED C. LOUNSBURY, a citizen of the United States, residing at Plainfield, in the county of Union and State of New Jersey, have invented an Improvement in Door-Fastenings, of which the following is a specification.

The object of the present invention is to hold a door at any desired point to which it may be swung open, and to effect this without injury to the floor or carpet at the place where the fastening device is brought into action. With this object in view a wedge-bolt is made use of adapted to be laid upon the floor beneath the lower edge of the door, so as to block and hold such door and prevent the same moving in either one direction or the other, and when not in use this wedge-bolt is received by and held within a case or slide upon the door.

In the drawings, Figure 1 is a side view, partially in section, representing the wedge-bolt in position for holding the door. Fig. 2 shows the same parts with the wedge-bolt within the casing. Fig. 3 is a sectional plan view of the case and wedge-bolt, and Fig. 4 is a rear view of the wedge-bolt and spring-brace.

A portion of the door is shown at A, and of the floor at B, and upon the door a case C is secured near the lower and outer edge, and this case is made with vertical slideways 2.

The wedge-bolt D is made with a head 3 and with an inclined surface 4 and with a back bar 5, there being a slot between the back bar and the face of the wedge-bolt, and it is advantageous to make the end of the head 3 in line with the inclined surface 4 of the wedge, so that the head of the bolt may rest upon the floor at the same time as the inclined surface 4, as shown in Fig. 1, and in this position the door can be swung open and pressed upon the wedge-bolt, so that the wedge-bolt holds the door in the position to which it may be moved, and to protect the lower edge of the door from injury by contact with the wedge-bolt it is desirable to make a flange 6 at the back and lower end of the case C to set against the under edge of the door and take a larger bearing on the wedge-bolt.

The spring-link E is made double, with the

fold or loop passing through the slot between the back bar 5 and the front of the wedge-bolt, and the sides of the spring-link are adapted to set closely against the sides of the back bar 5, and the extreme ends 7 of the spring-link are turned out and pass into the slideways 2 of the case, and the parts are sprung into place, so that the ends 7 have sufficient friction in the slideways 2 to hold the spring-link E in any position to which it may be moved. Hence the link E can be used as a brace between the wedge-bolt and the door, as shown in Fig. 1, or when the wedge-bolt is lifted the back bar 5 thereof may be sprung in between the two parts of the spring-link E, and the ends 7 of the spring-link move upward in the slideways 2 until the wedge-bolt can be swung down into the case C, with the lower end of the spring-bolt entirely above the floor, and in this position the parts can remain when out of use; or there may be a loop F upon the case C, into which the lower end of the wedge-bolt D may be inserted.

If desired, a hole or mortise may be provided in the door-sill or in the floor, into which the lower end of the wedge-bolt D may be inserted for holding the door positively when it is shut.

The lower end of the case should be beveled on the same angle as the wedge-bolt, so that the parts can set against each other firmly when the wedge-bolt is below the case and door. The wedge-surface 4 and head 3 may be covered with felt.

By pushing against the small end of the wedge-bolt by the foot the bolt can be slid along on the floor in one direction, and the link E will draw it along the other way when the door is moved.

I claim as my invention—

1. The combination with a wedge-bolt, of a case adapted to be fastened to the surface of a door and a link connected at one end with the wedge-bolt and sliding at the other end in ways in the case for allowing the bolt to be laid upon the floor to act as a wedge for holding the door, substantially as set forth.

2. The case C having slideways 2 and the flange 6 at the lower end passing under the door, in combination with a wedge-bolt and

a spring-link extending from the wedge-bolt to the case, substantially as set forth.

3. A wedge-bolt having a back bar and a slot between the body of the bolt and the back bar, in combination with a spring-link passing through the slot and terminating as outward-projecting ends, a case having slide-ways receiving the ends of the spring-link and adapted to be fastened to the surface of

10 a door, substantially as set forth.

4. The wedge-bolt having an inclined surface 4 and head 3 and a back bar 5 with a

slot between the back bar and the body of the bolt, in combination with a link passing through the slot, a case adapted to receive 15 the upper end of the link and the wedge-bolt when not in use, substantially as set forth.

Signed by me this 15th day of December, 1896.

FRED C. LOUNSBURY.
